Watson C. Coleman
Attorney

UNITED STATES PATENT OFFICE.

WILLIAM FRANKLIN LAWS, OF GOVERNORS ISLAND, NORTH CAROLINA.

TETHER.

No. 819,561.

Specification of Letters Patent.

Patented May 1, 1906.

Application filed November 9, 1905. Serial No. 286,590.

To all whom it may concern:

Be it known that I, WILLIAM FRANKLIN LAWS, a citizen of the United States, residing at Governors Island, in the county of Swain 5 and State of North Carolina, have invented certain new and useful Improvements in Tethers, of which the following is a specification, reference being had therein to the accompanying drawings.

10 My invention relates to tethers, and more particularly to that class known as "travelers," one of the objects being to provide simple and inexpensive means for tethering or picketing an animal for the purpose of 15 grazing and the like, so that it may traverse a considerable area without danger of becoming entangled in the tethering-rope.

Other objects and advantages of my invention, as well as the structural features by 20 means of which these objects are attained, will be made clear by an examination of the specification, taken in connection with the accompanying drawings, in which the same reference-numerals indicate corresponding portions throughout, and in which—

Figure 1 is a perspective view of my complete device, showing one end of the tethering-rope connected with a cow; and Fig. 2 is a detail of parts.

30 1 designates vertical standards or uprights, having their lower ends firmly embedded in the earth, so as to be held securely in position. Stretched between the standards is a rope or cable 2, along which is adapted to 35 travel a pulley 3, from which depends a ball and socket 4, having suspended therefrom the pulleys 5 and 6. Secured to the pulley 5 is the tethering-rope 7, which supports the pulley 6, and from said pulley 6 a weight 8 is 40 suspended, said pulleys 5 and 6 and the tethering-rope 7 forming, in effect, a block-and-tackle arrangement. The weight 8 is only 45 sufficiently large to keep the rope 7 taut and may be varied according to the strength or size of the animal tethered. In order that said animal may not pass around the uprights 1, and thus become fastened in any manner or its movements limited thereby, I provide the blocks 9, which are provided with

50 a longitudinal groove 10, through which the rope or cable 2 extends, and also with set or thumb screws 11, whereby said blocks may be tightened to grip the rope or cable 2 in such manner as to be held securely in position.

55 As the pulley 3 travels along said rope or ca-

ble in either direction it comes in contact with one of said blocks 9 and is stopped thereby, so that the extent of the travel of the pulley 3 is limited according to the points at which said blocks are secured on said rope 60 2. As the animal moves about over the ground the ball-and-socket arrangement 4 admits of the rotation of the pulleys 5 and 6. Consequently the rope 7, leading from the neck of the animal, cannot become entangled 65 in the arrangement of parts held suspended from the rope or cable 2.

The construction and operation of this device, it is believed, will be obvious from the foregoing description, and further explanation is not deemed necessary.

Having thus described my said invention, what I claim as new, and desire to secure by Letters Patent of the United States, is—

1. In a device of the character described, 75 vertical uprights, a cable stretched between said uprights and held suspended thereby, a pulley adapted to travel along said cable, a plurality of blocks each having a longitudinal groove therein to span the cable, set- 80 screws arranged in the blocks and adapted to bring the edges on each side of the groove closer together to grip the cable and thereby hold the blocks in adjusted position, and to release the edges to permit of adjustment of 85 the blocks longitudinal of the cable, the blocks being adapted to limit the travel of the pulley, a second pulley, a ball-and-socket connection between said pulleys, a tethering-rope having one end depending from the sec- 90 ond-mentioned pulley and the other end passing over it and thence to the animal whereby said animal is tethered, and a weighted pulley engaging the tethering-rope whereby the same is held taut against the movements of 95 the animal.

2. A device of the character described comprising the uprights 1, the rope or cable 2 stretched horizontally therebetween and having its ends fixedly secured thereto, the pulley 3 adapted to travel along said rope or cable, the grooved or slotted blocks 9 engaged with said rope or cable and adjustably secured thereon by the set-screws 11 for limiting the movement of said pulley, the second 100 pulley 5, the ball-and-socket connection 4 between said pulleys 3 and 5, the members of said connection permitting of a free axial or rotary movement and a limited angular movement of said pulleys with respect to 105 110

each other and having a loose or link connection with said pulleys, the third pulley 6 having the weight 8 removably suspended from it, and the tethering-rope 7 passed under the 5 pulley 6 and over the pulley 5 and having one of its ends attached to the pulley 5, substantially as described and for the purpose set forth.

In testimony whereof I hereunto affix my signature in presence of two witnesses.

WILLIAM FRANKLIN ^{his} X LAWS.
